PATENTED JAN. 21, 1908.

G. G. FLOYD.
CAR TRUCK.
APPLICATION FILED APR. 11, 1907.

UNITED STATES PATENT OFFICE.

GEORGE G. FLOYD, OF GRANITE, ILLINOIS, ASSIGNOR TO AMERICAN STEEL FOUNDRIES, OF NEW YORK, N. Y., A CORPORATION OF NEW JERSEY.

CAR-TRUCK.

No. 877,185.

Specification of Letters Patent.

Patented Jan. 21, 1908.

Application filed April 11, 1907. Serial No. 367,512.

To all whom it may concern:

Be it known that I, GEORGE G. FLOYD, a citizen of the United States, residing at Granite, in the county of Madison and State of Illinois, have invented certain new and useful Improvements in Car-Trucks, of which the following is a specification.

My invention concerns an improved cast-metal railway car-truck side-frame, and its 10 advantages and benefits arise because of the capability of producing more perfect and reliable castings of the character mentioned than has heretofore been possible.

It has been customary to make cast side- 15 frames with top compression members of channel shape in cross-section with its pair of parallel marginal flanges extended downwardly, and it has been usual to form the channel shape of this member by means of a 20 dry sand core anchored or supported in the green sand forming the greater portion of the mold. In a mold of this character there is a junction or meeting of the green sand and the dry sand core at a point on the tension 25 member of the frame. It has been found that the tension members of such side-frames made in this manner have weak places at such junctions and fail in service at this point. There are several theories re- 30 garding the reason for these defects at the places mentioned, but they need not be considered since a statement of the fact of the defect, such as air-holes or the like, is sufficient for the present purpose. I have there- 35 fore invented a modified form of side-frame which can be cast without the use of a core in such position that it in conjunction with the green sand will render the lower tension chord or member of the frame defective. The 40 change though slight means much in the casting of these frames, and the need for such change was only discovered after considerable financial loss caused by making frames of the old style. The new form of 45 frame has a channel compression member, but the flanges instead of projecting downwardly extend upwardly. There is, therefore, no need of a junction of dry and wet or green sand at the side of the tension mem- 50 ber, and the avoidance of defects therein is secured.

Another feature of my invention is the joining of the two side-frames of the truck by angle or similar bars connected to the frames

near the top thereof instead of near the bottom as is usual.

On the accompanying drawing forming a part of this specification Figure 1 is a fragmentary view illustrating the manner of casting a portion of the old style of frame; Fig. 2 is a section on line 2—2 of Fig. 1; Fig. 3 is a side elevation of my improved form of side-frame; and Fig. 4 is a plan of a fragment of the side-frame shown in Fig. 3 on an enlarged scale and other parts.

In Fig. 1 I have illustrated the manner of casting the old style of car-truck side-frame having a top channel compression member with depending flanges. The channel shape of the compression member or recess on its under side is produced by means of a dry sand core 10 suitably anchored and supported in the green sand 11 which forms the mold cavity for the greater portion of the side-frame. Preferably the core 10 is seated in a 70 recess 12 in the green sand 11 in order to properly support the same, and it will be noticed that at the point 13 on the tension member 14 of the side-frame a junction of the green sand and the dry sand core is formed. 75 Experience has shown that a side-frame produced in a mold of this character has defects at the points 13 on the tension member, these defects being a weakness probably due to air holes or the like. The defect mentioned is 80 sufficient to render the side-frames subject to breakage during ordinary usage, and air holes or other defects in the tension member of a side-frame are far more objectionable 85 than in a compression member. To overcome the difficulty mentioned above and to produce perfect and strong castings, I have devised a side-frame like that shown in Fig. 3 which has a top compression member 15 of 90 channel shape in cross-section, its web 16 being horizontal and having extended upwardly from its opposite edges parallel marginal flanges 17. As is obvious, such a side-frame 95 may be cast without a core for the production of its channel compression member, and for 100 this reason castings of this form may be made without the defects of the old style of side-frame shown in Fig. 1.

I have found that in some forms of trucks, the side-frames of which are connected together near their lower portions by means of angle or similar bars, it is difficult to remove the bolster, especially if the same has a con-

siderable depth, owing to the inability to lower the bolster sufficiently because of the presence of the transverse connecting bar or bars. Consequently, I have decided to dispense with the use of transverse tie bars at the lower portion of the side-frames, and bind the two frames on opposite sides of the truck together by means of bars positioned near the top of the frame. In order to provide convenient means for the attachment of such transverse bars, I cast integral with the side-frames shown in Fig. 3 inwardly and outwardly-extended lugs 18 and 19 at the inner edges of the triangular openings 20 on either side of the centrally disposed bolster opening 21. To the under side of the compression web 16 and adjacent to the ears or lugs 18 and 19 I rivet a pair of comparatively wide braces or gusset plates 22 which extend both inwardly and outwardly beyond the edges of the side-frame. To tie together the pair of side-frames of the truck I prefer to use transverse angle bars 23 each of which has a horizontal leg riveted to one pair of the plates 22 and to the web 16, and also has a depending vertical leg riveted or otherwise secured to a pair of the oppositely extended ears 18 and 19 on each frame. By the use of such transverse bars the side-frames are securely fastened together, and by the employment of the comparatively wide brace or gusset plates 22 the frame is considerably stiffened. It will be noticed that these angle bars 23 in no way interfere with the insertion of the bolster through the aperture 21 or its removal therethrough.

Ordinary mechanical changes may be made in the structure shown and described without departure from my invention and without sacrificing its benefits and advantages.

I claim:

1. A cast-metal truck side-frame having a top compression member of channel shape in cross-section the flanges of the channel extending upwardly away from the frame, substantially as described.
2. In a railway car truck, the combination of a pair of side-frames each having a top compression member and an integral lateral

lug or ear, a brace or gusset plate fastened to the compression member of each of said side-frames, and a transverse bar riveted to said brace plates and lateral lugs or ears, substantially as described.

3. In a railway car truck, the combination of a pair of side-frames each having a top compression member of channel shape in cross-section and a lateral lug, a brace plate fastened to the web of each of said top compression members, and a transverse angle bar having its angularly-disposed members riveted respectively to said brace plates and lateral lugs or ears, substantially as described.

4. In a railway car truck, the combination of a pair of side-frames each having a top compression member of channel shape in cross-section with its flanges extended upwardly, and one or more transverse bars connecting said side-frames and riveted to the under surfaces of the webs of said compression members, substantially as described.

5. In a railway car truck, the combination of a pair of side-frames each having a top compression member of channel shape in cross-section with its flanges extended upwardly and also having laterally extended lugs or ears projecting from each side, one or more brace or gusset plates fastened to the under surface of the web of each of said channel compression members adjacent to said lugs or ears, and one or more transverse angle bars connecting said side-frame, each having its angularly-disposed members riveted respectively to said brace plates and lateral lugs, substantially as described.

6. In a railway car truck, the combination of a pair of side frames each having a top compression member, a centrally disposed bolster opening and other openings on opposite sides of said bolster opening, and transverse tie bars connecting said side-frames, extended through said openings on opposite sides of the bolster openings and riveted to the under surface of the top compression members, substantially as described.

GEORGE G. FLOYD.
